Filed Feb. 17, 1961, Ser. No. 90,018
7 Claims. (Cl. 181—46)

This invention relates to means for muffling or silencing the exhaust of internal combustion engines and particularly to an improved form thereof characterized by a minimum of elements offering opposition to the free flow of the exhaust gases and the expansion thereof.

The principal object of this invention is to provide an exhaust silencing means for the engines of automotive vehicles characterized by means utilizing the impulses or surges of the exhaust from opposite groups or banks of cylinders of the engine to oppose and cancel out each other with resultant primary diminution of the noise from the exhaust.

Another object of the invention is to provide a silencer for the exhaust of V-type vehicle engines in which half of the exhaust emissions of both banks of engine cylinders are directed into one expansion chamber and the other half into another expansion chamber by conduit means of equal length and in which other, separate means are provided downstream of each of said expansion chambers for separately further absorbing the sound producing vibrations deriving from the remaining impulse traces in the separate streams of exhaust gases.

With the above objects in view, together with such additional objects and advantages as may subsequently appear, the invention resides in the parts, and in the construction, combination and arrangement of parts described, by way of example, in the following specification of a presently preferred embodiment of the invention, reference being had to the accompanying drawings which form a part of said specification and in which drawings:

FIG. 1 is a somewhat diagrammatic top plan view of a representative vehicle chassis and motor to which the invention is applied.

FIG. 2 is enlarged side elevational view of the silencer unit.

FIGS. 3 and 4 are, respectively, front and rear elevational views of the silencer shown in FIG. 2.

FIG. 5 is a top plan sectional view taken on the staggered line 5—5 of FIG. 2, and

FIG. 6 is a transverse sectional view taken on the line 6—6 of FIG. 2.

Referring to FIG. 1 there is shown a plan view of a vehicle chassis including a motor M, a frame F, front wheels W and rear wheels W' connected to the motor end through drive shaft means D. The motor is of V-type having a left hand cylinder bank LC including an exhaust manifold LE having the front end thereof connected by an exhaust pipe 1 to a first inlet port thimble 2 of the silencer 3. The other cylinder bank RC includes an exhaust manifold RE having the rear end thereof connected by an exhaust pipe 4 to the second inlet port thimble 5 of the silencer 3.

The silencer 3 comprises an elongated, oval, sheet metal body 6 closed at its forward end by a wall 7 through which the inlet port thimbles 2 and 5 conduct the exhaust gases to the interior of the silencer. At its rear end the body 6 is closed by a wall 8 through which exhaust port thimbles 9 and 10 deliver the exhaust gases from the silencer.

The silencer is shown mounted below the vehicle frame in horizontal position parallel to the length of the vehicle and adjacent to the left hand side of the vehicle. It is of importance, as will be later explained, that the pipes 1 and 4 be of the same length, wherefor, as will

2

be noted the pipe 1 which is on the same side of the vehicle as the silencer extends from the front end of its manifold while the pipe 4, due to the fact that it extends laterally across the vehicle, connects from the rear end of its manifold. The major axis of the oval cross section of the silencer body is disposed horizontally and a longitudinally extending vertical wall 11 bisects the interior of the silencer into chambers 12 and 13. The inlet port thimbles 2 and 5 are disposed with the axial lines thereof coincident with the plane of said vertical wall as is best shown in FIGS. 3 and 6 and consequently one-half of the exhaust emissions of each bank of cylinders is diverted into the chamber 12 and the other half of the exhaust emissions is diverted into the chamber 13.

The outlet port thimbles 9 and 10 (see FIG. 4) are disposed at opposite sides of the wall 11 and the outlet port thimble 9 conducts all of the gases from the chamber 12 into a pipe 14 leading to a glass fiber packed secondary muffler 15 and a separate tail pipe 16 delivers the gases to atmosphere. Correspondingly, the exhaust port thimble 10 conducts all of the gases from the chamber 13 into a pipe 17 leading to a corresponding secondary muffler 18 and a tail pipe 19 delivers the gases to atmosphere. By this arrangement, it will be noted that each tail pipe receives and discharges one-half of the total exhaust emission from both banks of engine cylinders.

Due to the identical length of pipe 1 and 4, the exhaust impulses of the various cylinders of the left bank will reach the silencer 3 in the same time intervals as the corresponding impulses from the right hand bank of cylinders. By way of example, as an exhaust impulse from the left hand bank of cylinders enters the chambers 12 and 13 through the inlet port thimble 4 and then starts to expand in a downwardly and rearwardly moving surge, it is met almost immediately by an equivalent rearwardly and upwardly moving surge from an exhaust impulse received from the right hand bank of cylinders entering the chambers 12 and 13 through the inlet port thimble 5 and that impulse or surge in turn is met and opposed by the next following surge or impulse received from the left hand bank of cylinders. Since the frequencies are the same, these impulses tend to cancel each other out and as the gases flow through the respective exhaust port thimbles they have an almost uniform velocity, wherefore, such flow is substantially noiseless. Any remaining pulsations in the exhaust are substantially eliminated by the individual, secondary glass fiber packed mufflers 15 and 18. Since there are no opposing baffles or the like, there is practically no back pressure on the exhaust other than the frictional engagement with the various pipes and hence there is no loss of engine power by reason of exhaust back pressure. Furthermore, the device is much more economical to manufacture since the primary silencer is formed with only a center longitudinal partition.

While the above disclosure relates to a presently preferred form of the invention it will be appreciated that the position of the silencer body 3 in the chassis dictates to a great extent the nature of the connection of the exhaust pipes 1 and 4. If this muffler would be located on the right hand side of the chassis, the arrangement of the exhaust manifolds would be reversed. On some vehicles it is possible that it would be located near the center of the vehicle, in which case, both exhaust pipes might well lead from the rear end of the respective exhaust manifolds. Further, while the inlet ports are shown as located in the vertical plane, it may be that for some installations it will be found more practical and advisable to position the silencer body rotated 90°

from the illustrated position with the wall 11 disposed horizontally with the inlet ports located laterally spaced from each other and the outlet ports disposed vertically.

Having these and other modifications in mind, it will be understood that the invention is not to be deemed to be limited to the precise form thereof disclosed by way of example and it will be understood that the invention includes as well all such changes and modifications in the parts and in the construction, combination and arrangement of parts as shall come within the purview of the appended claims.

I claim:

1. In a silencer for the exhaust of a V-type internal combustion engine, an elongated hollow metal body having a pair of walls closing the opposite ends thereof and further having partition means dividing the interior thereof into two, longitudinally extending, parallel, substantially identical chambers, a first conduit means including an inlet port formed in one of said end walls operative to conduct the entire exhaust from one bank of engine cylinders into said body, a second conduit means including a port formed in said one wall of said body operative to conduct the entire exhaust from the other bank of engine cylinders into said body; each of said inlet ports having adjacent to the downstream end thereof an exhaust gas flow diverting means operative to divert the exhaust gases received in each of said inlet ports into said chambers in substantially equal proportions, a first exhaust discharge port formed in another wall of said body effective to discharge all of the exhaust gases delivered into one of said chambers, and a second discharge port formed in said other wall of said body effective to discharge all of the exhaust gases delivered into the other of said chambers.

2. A silencer means as claimed in claim 1 in which said first named conduit means for conducting exhaust gases to said chambers and said second named conduit means for conducting exhaust gases to said chambers are of substantially equal length.

3. A silencer means as claimed in claim 1 including separate tail pipes each having a separate muffler for discharging exhaust gases received from said discharge ports to atmosphere.

4. In a silencer for the exhaust for V-type internal combustion engines having separate exhaust manifolds for each bank of cylinders, an elongated, hollow metal body having walls closing each end thereof, a medial partition extending between said end walls and dividing the interior of said body into two chambers, a pair of

inlet ports extending through one of said end walls and disposed with the axial lines thereof in the plane of said partition, a pair of exhaust pipes connecting one each of said exhaust manifolds with one each of said inlet ports whereby exhaust gases entering said body through each of said ports is delivered in substantially equal quantities into both of said chambers, and a pair of exhaust ports in the other of said end walls and disposed one each at each side of said partition whereby each of said exhaust ports delivers all of the exhaust gases from one each of said chambers.

5. An exhaust silencer as claimed in claim 4 in which said exhaust pipes are of equal length.

6. In a silencer for the exhaust of V-type vehicle engines having separate exhaust manifolds for each bank of cylinders, a hollow metal body of greater length than diameter disposed beneath the vehicle chassis adjacent one side thereof and having a front wall and a rear wall, a partition extending between said walls and dividing the interior of said body into two substantially identical chambers, a pair of inlet ports formed in and extending through said front wall and disposed with the axial lines thereof disposed coincident with the plane of said partition, an exhaust pipe connecting one of said inlet ports to the front end of the exhaust manifold serving the engine cylinder bank at the side of the vehicle chassis to which said silencer body is adjacent, a second exhaust pipe connecting the other of said inlet ports to the rear end of the exhaust manifold serving the other cylinder bank of the engine, and a pair of discharge ports in said rear wall communicating only one each with each of said chambers.

7. A silencer means as claimed in claim 6 in which each of said discharge ports is connected to one each of a pair of tail pipes.
